(57) **CLAIM**

The ornamental design for a trigger assembly, as shown and described.

DESCRIPTION

FIG. 1 is an exploded perspective view of a trigger assembly showing my new design;

FIG. 2 is a perspective view of the assembled trigger assembly in one position;

FIG. 3 is a perspective view of the assembled trigger assembly in an alternate position;

FIG. 4 is a left side elevation view thereof; the right side elevation view being a mirror image thereto;

FIG. 5 is a top plan view thereof;

FIG. 6 is a bottom plan view thereof;

FIG. 7 is a front elevation view thereof;

FIG. 8 is a rear elevation view thereof;

FIG. 9 is an exploded perspective view of an alternative embodiment of a trigger assembly;

FIG. 10 is a perspective view of the assembled alternative trigger assembly in one position;

FIG. 11 is a perspective view of the assembled alternative trigger assembly in an alternate position;

FIG. 12 is a left side elevation view thereof; the right side elevation view being a mirror image thereto;

FIG. 13 is a top plan view thereof;

FIG. 14 is a bottom plan view thereof;

FIG. 15 is a front elevation view thereof; and,

FIG. 16 is a rear elevation view thereof.

The broken lines in FIGS. 1 and 9 depict order of assembly as well as environmental structure in the exploded views, and form no part of the claimed design.
